(57) **CLAIM**

The ornamental design for a “sink cutting board,” as shown and described.

DESCRIPTION

FIG. 1 is a front perspective view of the sink cutting board, showing my new design;

FIG. 2 is a rear perspective view thereof;

FIG. 3 is a top plan view thereof;

FIG. 4 is a bottom plan view thereof;

FIG. 5 is a side elevational view, both sides being identical thereto; and,

FIG. 6 is an end elevational view, both sides being identical thereto, of the sink cutting board illustrated in FIGS. 1-4.

The broken lines shown in the drawings are for illustrating the environment of the sink cutting board and form no part of the claimed design.
